(57) **CLAIM**

The ornamental design for a mattress, as shown and described.

DESCRIPTION

FIG. 1 is a left side, top perspective view of a first embodiment of a mattress showing my new design;

FIG. 2 is a left side view thereof;

FIG. 3 is a right side view thereof;

FIG. 4 is a front view thereof;

FIG. 5 is a rear view thereof;

FIG. 6 is a perspective view of the first embodiment showing the mattress in an alternate environment; and,

FIG. 7 is a perspective view of the first embodiment showing the mattress in a second alternate environment and in an articulated position.

The broken lines are environmental and form no part of the claimed design.

1 Claim, 4 Drawing Sheets

FIG. 2

FIG. 3
